[57] CLAIM

The ornamental design for a combination battery charger, receiver and amplifier or similar article, substantially as shown.

DESCRIPTION

FIG. 1 is a perspective view of the combination battery charger, receiver and amplifier or similar article showing the front, one side and the top of our new design; FIG. 2 is an elevation view showing the side of the combination battery charger, receiver and amplifier or similar article shown in FIG. 1;

FIG. 3 is a plan view showing the bottom of the combination battery charger, receiver and amplifier or similar article shown in FIG. 1;

FIG. 4 is an elevation view showing the rear side of the combination battery charger, receiver and amplifier or similar article shown in FIG. 1.

FIG. 2

FIG. 4
